UNITED STATES PATENT OFFICE

HARRY JOHNSON, OF SWEETWATER, NEBRASKA

TRAFFIC SIGNAL

Application filed January 20, 1928. Serial No. 248,200.

The present invention is directed to improvements in traffic signals, and has for its primary object to provide a device of this character capable of being installed upon a vehicle and conveniently operated for indicating to following traffic the intended course of the vehicle equipped with the device.

Another object of the invention is to provide a device of the character specified, so constructed that the signal will be illuminated when the arm thereof is extended and extinguished when the arm is contracted.

Another object of the invention is to provide a device of this character so constructed and arranged that the driver of a vehicle equipped with the device can indicate to approaching and following traffic, as well as to pedestrians, the intended course of the vehicle, without the necessity of extending the arm therefrom, which is now customary, and while no doubt, effective, nevertheless adds to the discomfort of the occupants of the vehicle in cold weather, since to do so necessitates opening the window next the driver.

Another object of the invention is to provide a device of this character which is neat in appearance, effective in operation, and one which can be manufactured at a very small cost.

Still another object of the invention is to provide a signal of this class which will occupy a minimum space when in its inoperative position, but can be extended for a considerable length for signalling, and is controlled from the interior of the vehicle.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a fragmentary front view of a

vehicle showing the device attached thereto and in its extended or operative position.

Figure 2 is a sectional view on line 2—2 of Figure 1.

Figure 3 is a view similar to Figure 1, showing the signal collapsed, or in its inoperative position.

Figure 4 is a sectional view on line 4—4 of Figure 3.

Figure 5 is a rear view of the switch casing showing the cover plate removed.

Figure 6 is a sectional view on line 6—6 of Figure 5.

Figure 7 is a modified form showing means to prevent tilting of the lamp.

Corresponding and like parts are referred to in the following description and designated in the several views of the drawings by like reference characters.

Referring to the drawings, 1 designates the front frame of a motor vehicle, and to the vertical sill 2 thereof are secured the upper and lower ends of the guide rod 3. Near the upper end of said rod is a bracket 4, while slidably thereon below said bracket, is a sleeve 5, the purpose of which will be later explained.

A lazy tong arm 6 is employed and has its innermost links 7 and 8 pivotally connected, respectively, to the bracket 4 and sleeve 5, while supported by the outermost links 9—9 of said arm is a lamp socket 10, in which is engaged the bulb 11, said bulb being confined in the lamp casing 12 supported by said socket. Leading from the socket is a circuit wire 13 which is connected to the binding post 14 of the switch 15, said binding post having a contact 16 upon its inner end, and it is through this wire that current is furnished for illuminating the bulb. The other binding post 17 supports a companion contact 18, there being a circuit wire 19 leading therefrom to the electric system of the vehicle.

Slidable in the casing 20 is a spring restrained bar 21 having a block 22 of insulating material fixed thereon which carries the resilient contact arms 23 for simultaneously engaging the contacts 14 and 18 when the bar is drawn upwardly in order to close the circuit.

cuit and illuminate the casing when the arm 6 is extended. A coil spring 24 connects the lower end of the bar to the sill 2 to aid in retracting the bar.

The upper end of the bar 21 has connected thereto the lower end of the cord or wire 25, the upper end of which is secured to the sleeve 5.

A ground wire 26 leads from the lower end of the rod 3 in order to complete the circuit when the switch is closed.

In order that the arm 6 can be conveniently extended a link 27 is provided and has its outer end pivotally connected to the arm 6, and its inner end pivoted to an arm 28 fixed to a crank 29 journaled in the top sill 30 of the vehicle frame.

As shown in Figure 3 the arm 6 is collapsed, or in its inoperative position, and when it is desired to extend the same to signal, the crank is rotated in a direction to move the link 27 outwardly which exerts its force upon said arm to extend the same. As soon as the signal has been operated the crank is released, whereupon the spring 31, which connects the arm 28 and sill 30, aided by the spring 24, will automatically collapse the arm 6, thus again moving the casing to its inoperative position.

Obviously, when the arm is extended the sleeve 5 will travel upwardly on the rod 3, thus pulling the cord or wire 25 whereupon the rod 21 will be moved upwardly in order that the contact arm 23 will engage the contacts 14 and 15, thus completing the circuit and illuminating the casing. Of course when the arm is collapsed the signal will be extinguished.

Since the crank is conveniently located the driver of the vehicle can quickly grasp the same and extend the signal when a turn is to be made, and any suitable indicia may be supplied to the lamp casing, and while the device is shown as used in connection with a closed vehicle, it will be of course understood that it can be applied to the open type as well.

In Figure 7 the arm 6 has pivoted to one outer link 9 a long link 32 which rigidly supports the bracket 33 bearing the lamp 34, the link 32 being connected to the other link 9 by a short link 35. In this manner the bracket 33 will maintain the lamp against tilting.

Having thus described the invention, I claim:

Vehicular signaling means including a vertical rod secured at its upper and lower ends to the vehicle and spaced therefrom intermediate its ends, a lazy tong mounted on said rod and provided at its outer end with a signal, an operating member disposed between the vehicle and the beforementioned vertical rod and pivoted to the lazy tong, a crank mounted on the vehicle, an arm connected with the crank and having the inner

end of the said operating member pivoted thereto, and a contractile spring associated with the crank and operating member to restore the parts to normal position after being actuated.

In testimony whereof I affix my signature.

HARRY JOHNSON. [L. S.]
